UNITED STATES PATENT OFFICE.

BYERS W. KADEL, OF BALTIMORE, MARYLAND, ASSIGNOR TO THE SYMINGTON COMPANY, OF NEW YORK, N. Y., A CORPORATION OF MARYLAND.

SIDE FRAME.

Application filed June 2, 1925, Serial No. 34,422. Renewed December 19, 1927.

This invention relates to side frames for railway car trucks and more particularly to the reinforcement of the ends of cast side frames.

5 The principal object of my invention, generally considered, is the reinforcement of the union between compression and tension members at the ends of cast side frames for railway car trucks.

10 An object of my invention is the strengthening of the junction between the compression and tension members at the ends of side frames for railway car trucks, which side frames may be provided with integral journal boxes by carrying flanges from the tension member beyond the junction of the compression and tension members, said flanges being preferably formed in line with the general direction of the tension member.

15 Another object of my invention is the strengthening of the connection or junction at the ends of side frames for railway car trucks adjacent the union with integral journal boxes, and particularly in connection with cast frames in which the compression and tension members are formed generally U-shape in cross-section and in which each member comprises a web and flanges at opposite sides of said web, ribs being provided in line with the upper edges of the flanges on the tension member and extending from below the intersection of the compression member therewith to above said intersection and extending for a material distance along the outer ends of the compression member.

20 Another object of my invention is the provision of reinforcing ribs on the outer faces of side frames for railway car trucks, said ribs being located adjacent the junction between compression and tension members and extending preferably in line with the upper edges of the tension member from below to above the junction of the compression member therewith and preferably being swelled or increased in strength at approximately said junction and decreased in both directions therefrom.

25 Other objects and advantages of the invention will become apparent as the description proceeds.

Referring to the drawings illustrating my

invention, the scope whereof is defined by the claims:

Figure 1 is a fragmentary side elevation 55 of one end of a side frame for railway car trucks embodying my invention; and

Figure 2 is a fragmentary plan view of the side frame as illustrated in Figure 1.

Referring to the drawings in detail, like 60 parts being designated by like reference characters, I have shown one end of a side frame 1 for railway car trucks, the remainder of said frame not involving features of my present invention not being il- 65 lustrated.

In the embodiment shown the frame comprises a compression member 2 and tension member 3, the ends of said compression and tension members being integrally united at 70 4, as is usual in cast side frames, and preferably formed with a journal box 5 adjacent the point of union between compression and tension members at the ends of the frame.

The frame 1, as will be understood, is 75 symmetrical on either side and may be formed, as is usual, with bolster column or strut portions spacing intermediate portions of the compression and tension members. Such features, however, not being part of 85 my invention and well known to those skilled in the art, are not illustrated.

The compression member 2 and tension member 3 extends substantially the full length of the side frame, as will be understood, and at each end of said side frame there is provided a journal box 5 preferably integral therewith. Said compression and tension members in the present embodiment are each formed generally U-shape in cross- 95 section with a main web portion 6 and flange portions 7 on opposite sides of the web portion, said flange portions, in the embodiment shown, extending inwardly or toward each other. The free edges of the flange portions 100 7 may be thickened or provided with rib or bead portions 8 extending therealong.

From a consideration of the drawing, it will be apparent that in the present embodiment the tension member is formed with a 105 bottom web and upstanding flanges at opposite sides of said web, whereas the compression member comprises an upper or top web with depending flanges on opposite sides

thereof. The outer portions of the web 6 of the compression member 2 are preferably sloped downwardly and outwardly and curved to connect with the outer wall of each journal box 5, at 9. The outer portion of the web of the compression member, therefore, is curved at its outer ends from an approximately horizontal to an approximately vertical position, where it merges with the outer wall of the journal box. However, the construction may be lightened, if desired, as illustrated, by cutting away a portion of the web 6 of the compression member adjacent the connection with the journal box. The corresponding flange portions 7 of the compression and tension members 2 and 3 merge into each other, at 10, to form a box-like portion over each journal box.

20 The union between the web 6 of the tension member 3 and the journal box is preferably made by curving said web slightly at 11 to an approximately horizontal position and joining it with the roof or upper wall 12 of the journal box. The central portion of the web at this point may be cut away at 13, if desired, to lighten the construction.

Approximately triangular reinforcing webs 14 may be provided between the outer portion of the web 6 of the tension member and the inner wall 15 of each journal box. The junction between the compression and tension members is reinforced by flanges or rib portions 16 in line with the upper edge of the flange portions 7 of the tension member 3 and extending from below the junction 4 between the compression and tension members to above said junction, as illustrated. These flanges or ribs 16 preferably increase in depth, width or strength from the ends thereof to a maximum adjacent the junction 4 between compression and tension members.

Although the flanges or ribs 16 are shown on the outside faces of the side frame, they may be formed on the inside faces thereof instead of, or in addition to, being formed on the outside faces thereof.

From a consideration of the drawings it will be apparent that these flanges or ribs are preferably formed as enlargements and continuations of the thickened or beaded portions 8 forming the upper edges of the flanges on the tension member 3. The ribs or beading 8 on the lower edges of the compression member preferably curve around the junctions with the tension member as indicated at 4, and merge with the ribs 16. Although the reinforcement flanges are shown as extending nearly entirely across the outer ends of the compression member 2, I do not wish to be restricted to the exact length of said flanges as said length, as well as the depth, width or strength thereof, may be increased or decreased according to circumstances. Such a reinforcement, however, as

illustrated, which merely adds a slight proportion of material to the frame, will greatly increase the strength thereof because said reinforcing flanges or ribs are positioned at critical portions of the frame.

70

Having now described my invention, what I claim is:

1. A car truck side frame comprising a compression member and a tension member, said members converging at their ends and united together, and the junction between said members being reinforced by flanges from the sides of the tension member extending in line with the top of said member and merging into the side of the compression member below the upper edge thereof.

75

2. A car truck side frame comprising a tension member and a compression member, said members converging at their ends and united together, and each being formed with a web and flanges extending therefrom, the junctions between said members being reinforced by flanges disposed generally in line with the free edges of the flanges of the tension member and extending partly across the ends of the compression member.

80

3. A car truck side frame comprising a compression member and a tension member, said members converging at their ends and united together, the junctions therebetween being reinforced by flanges extending diagonally only partly across the compression member from the junction between the tension and compression members and generally in line with the tension member.

95

4. A car truck side frame comprising a compression member and a tension member, said members converging at their ends and united together and to journal boxes, the junctions between said members and journal boxes being reinforced by flanges extending from those portions of the tension member adjacent the compression member diagonally upward across the outer faces of the side walls of the frame below the ends of the compression member.

105

5. A car truck side frame comprising a compression member and a tension member converging at their ends and united together and to journal boxes, the junctions between said members and journal boxes being reinforced by ribs extending along the faces of the side frame between the tension member and those portions of the side frame adjacent the junction with the compression member, said ribs being increased in strength adjacent the junction of compression and tension members and decreasing therefrom to their ends.

115

6. A car truck side frame comprising a compression member, a tension member generally U-shape in cross-section and formed with a bottom web and upstanding flanges at the sides thereof, the junctions between the compression and tension mem-

120

125

130

- bers being reinforced by flanges on the sides of the tension member in line with the upper edges of the flanges thereof and extending from below to above the junctions between 5 compression and tension members.
7. A car truck side frame comprising a compression member, a tension member generally U-shape in cross-section and formed with a bottom web and upstanding flanges 10 at the sides thereof, the upper edges of said flanges being thickened or beaded, and a journal box at each end of the frame and joined thereto adjacent the junctions of the compression and tension members, said junctions being reinforced by ribs disposed generally in line with and as continuations of the beading or thickened portions of the flanges on the tension member and extending along said tension member beyond the 15 junctions with the compression member.
8. A car truck side frame comprising a compression member, a tension member generally U-shape in cross-section formed with a bottom web, and upstanding flanges at 20 the sides of said web, and a journal box at each end of the frame and joined thereto adjacent the junction of the compression and tension members, the junctions between the frame members and journal boxes being reinforced by flanges extending adjacent the 25 junctions between the tension and compression members and below the ends of the compression member.
9. A car truck side frame comprising a compression member, a tension member, said members being generally U-shape in cross-section and each formed with a web and flanges at the sides of the web, and a journal box at each end of the frame and joined 30 thereto adjacent the junction of compression and tension members, the junctions between the compression and tension members and journal boxes being reinforced by ribs extending from those portions of the tension 35 member adjacent the compression member diagonally upward across the outer faces of the side walls of the portions of the side frame above the journal boxes and partly below the ends of the compression member.
- 40 10. A car truck side frame comprising compression and tension members generally U-shape in cross-section each formed with a web and flanges extending therefrom on opposite sides of the web and a journal box 45 at each end of the frame integrally joined thereto adjacent the junction of compression and tension members, the junctions between the compression, tension and journal box members being reinforced by flanges extending 50 along the faces of the side frame between the tension member and those portions of the side frame adjacent the junction of the compression member therewith, said flanges being generally in line with the free 55 edges of the flanges of the tension member and increased in strength to a maximum adjacent the junction of the tension and compression members and decreasing in strength therefrom to their ends.
11. A truck side frame comprising a compression member and a tension member converging at their ends and united together and to journal boxes, the junctions between said members being reinforced by ribs extending from the sides of the members, and 60 said ribs being increased in strength adjacent the junction between compression and tension members and gradually decreasing therefrom toward their ends.
12. A truck side frame comprising a compression member generally U-shaped in cross section and formed with an upper web and depending flanges at the sides thereof, a tension member generally U-shaped in cross section and formed with a lower web and 65 upstanding flanges at the sides thereof the free edges of said upstanding flanges being reinforced by ribs which are increased to a maximum in strength adjacent the junction between said compression and tension members. 70
13. A truck side frame comprising a compression member, a tension member generally U-shaped in cross section and formed with a bottom web and upstanding flanges 75 at the sides thereof the upper edges of said flanges being thickened or beaded, and a journal box at each end of the frame and joined thereto adjacent the junctions of the compression and tension members said junctions being reinforced by increasing the strength of the beading or thickened portions of the flanges adjacent the junctions with the compression member. 80
14. A car truck side frame comprising a compression member and a tension member, said members converging at their ends and united together and to journal boxes, the junctions between said members and journal boxes being reinforced by flanges extending 85 from the junctions of the tension member with the compression member diagonally upward in substantial alignment with the top of the tension member. 90
15. A cast side frame comprising a compression member, a tension member and journal boxes integrally united at the ends thereof, the lower edge of the compression member being formed with ribs curving downwardly around the junctions with the tension member, ribs being provided extending diagonally upward and outward along the sides of the frame from the lower ends of the compression member ribs, in substantial alignment with the top of the tension member, for reinforcing the junctions between said compression member, tension member and journal boxes. 95

In testimony whereof I affix my signature.
